UNITED STATES PATENT OFFICE

2,567,379

TERMINAL DEVICE FOR ABSORBING
ELECTROMAGNETIC ENERGYOrwald E. Kienow, South Acton, Mass., assignor
to Raytheon Manufacturing Company, Newton,
Mass., a corporation of Delaware

Application July 20, 1944, Serial No. 545,839

3 Claims. (Cl. 178—44)

1

This invention relates to a means for terminating a coaxial transmission line, a hollow wave guide or other pieces of high frequency electrical equipment in an infinite line.

In the development and testing of ultra high frequency equipment it is frequently desired to provide a terminal device which may be readily connected to the element under test and which will provide a termination for the same having the characteristics of an infinite line.

It is among the objects of the invention to provide a terminal device such that when looking into the device from the piece of electrical equipment under test the impedance will be equivalent to the impedance of an infinite line.

It is a further object of the invention to provide a method for manufacturing such terminal devices.

A further object of the invention is to provide a terminal device which may be readily assembled in conjunction with the electrical apparatus tested.

The above and other objects and features of the invention will be fully apparent to those skilled in the art from a consideration of the following detailed description taken in conjunction with the accompanying drawing in which:

Fig. 1 represents a longitudinal section through a terminal device of the coaxial line type constructed in accordance with the invention;

Fig. 2 shows, on a reduced scale, a detail of a portion of the device shown in Fig. 1 in the process of manufacture;

Fig. 3 represents a longitudinal section through another form of the terminal device constructed in accordance with the invention and suitable for use in conjunction with hollow wave guides; and

Fig. 4 is a section taken on line 4—4 of Fig. 3.

Referring to the drawing, and first to Figs. 1 and 2 thereof, there is shown a coaxial line comprising an outer conductor 2 and an inner coaxial conductor 3. The outer conductor is preferably constructed of a plurality of sections comprising end sections 4 and 5 which may be of copper tubing or other conductive material, and a central support section 6 also of conductive material. The outer end of the section 4 is closed by end plug 7 and the outer end of section 5 is preferably provided with a flange 8 for readily connecting the device to some piece of electrical equipment to be tested. The inner conductor 3 is likewise of conductive material and is preferably formed in two sections, the outer section 9 of which is supported in concentric relation to the end section 4 by a machine screw 10 extending

2

through the end plug 7 and coaxing with an internally threaded bore in the end of the section 9. The opposite end of the section 9 is connected to a support section 11 by a suitable socket connection. The central support section 6, which for the sake of rigidity may be of thicker material than the end sections 4 and 5, includes a stub support 12 which in the instance shown is a quarter wave stub line. However, it will be understood that the support for the inner coaxial conductor at this point may be of the same type as that shown in the copending application of Joseph Goldsmith, Serial No. 522,489, filed February 15, 1944. Preferably the coaxial conductor 3 is provided with a transformer 13 comprising an enlargement thereof extending for a quarter wave length on each side of the axis of the stub support 12 for the purpose of cancelling any reflections due to the support. In order to terminate the device in a line, which looking in the direction of the end plug 7 will appear to be of infinite length and accordingly have no reflections, I provide a covering on the section 9 of the coaxial line, which covering gradually increases in diameter toward the end plug 7 until the covering completely fills the space between the inner conductor and the outer conductor 4. The covering must be of a material which is a good absorber of high frequency waves and I have found that a material impregnated with a rubber compound high in carbon black is ideal for this purpose. Preferably the material impregnated is cotton cloth and the impregnating compound is sufficiently high in carbon black to provide conduction paths of high resistance between adjacent particles. Low concentrations of carbon black so fully dispersed in rubber that there can be no conduction between adjacent particles are not suitable for the purposes of the present invention.

In the manufacture of the device the impregnated cloth 14 is cut in the form of a triangle having one side of approximately the same length as the length of the section 9 of the coaxial conductor. The triangular strip is attached to the section 9 along this side thereof and the section 9 is rotated so that the cloth is wound upon this section. As the cloth is wound on the section 9, successive layers of the cloth build up a continuously increasing thickness of impregnated material in the direction of the long side of the triangular strip 14. Thus as shown at the right hand end of the section 9 there is but one layer of the impregnated material, the number of layers successively increasing toward the left until, when

the cloth is fully wound upon the section 9, the largest diameter of the covering formed in this manner is substantially equal to the internal diameter of the outer conductor 4.

It will be understood that the length of the section of the conductor which is covered in this manner is made as long as possible in order that the taper of the covering will be as gradual as possible. I have found that in a coaxial line where the internal diameter of the outer conductor is about 0.811 inch and the diameter of the inner conductor is about 0.375 inch, if the length of the section 9 is about 13 inches, a sufficient taper in the covering of the material is provided. Under these conditions the length of the side of the triangular strip attached to the section 9 will be approximately 13 inches and the length of this strip, taken on the long side of the triangle, will be approximately 44 inches. With these dimensions the covering at the end of the section adjacent the long side of the strip will be sufficient to fill the coaxial conductor 4 with a sliding fit at the large end of the section 9.

In operation it will be understood that the device is adapted to be attached at the flanged end 8 to a piece of electrical equipment to be tested. If the piece of electrical equipment includes a coaxial conductor the inner conductor 3 is connected to the central conductor of the apparatus by a suitable socket connection, or if the equipment to be tested terminates in a hollow cylindrical guide the inner conductor 3 may be terminated therein by a suitable exciting rod. When so positioned, the device, as seen looking from the equipment under test in the direction of the end plug 7, provides an impedance equivalent to an infinite line.

Referring to the form shown in Figs. 3 and 4, reference numeral 21 indicates a section of a hollow rectangular wave guide having one end closed by an end plug 22 and having a flange 23 at the opposite end for connecting the device to a piece of electrical equipment to be tested. In this form of the invention an infinite impedance, as seen looking into the guide 21 toward the end plug 22, is provided by means of a block 24 forming a pyramidal or cone shaped structure gradually tapering from the end of the guide adjacent the flange 23 toward the end plug 22. Adjacent the plug 22 the block 24 has a rectangular base portion 25 dimensioned to fit tightly within this end of the wave guide 21. The structure 24 is preferably made of non-conductive material such as well seasoned wood and is preferably divided into two sections 26 and 27. Each of these sections 26 and 27 is separately covered on all of the surfaces thereof with a material 28 which is a good absorber of high frequency waves such as the cloth 14 described in the form of the invention shown in Figs. 1 and 2. In the form of the invention shown in Figs. 3 and 4, however, the tapering structure is not built up of the absorbent material but constitutes an absorbent screen covering, the non-conductive material forming the tapered block 24 and also forming a partition separating the two sections 26 and 27 of the block.

The form of the terminal device shown in these figures is adapted to be connected to some piece of electrical equipment having a rectangular wave guide and when so connected provides the equivalent of an infinite line looking in the direction of the end plug 22. Waves passing in the direction of the end plug are absorbed by the covering 28, which covering is so gradually

tapered that reflections therefrom are avoided. Any wave energy not absorbed by the covering on the outer or exposed surface of the block is absorbed by the absorbing material between the two sections 26 and 27. The structure thus prevents any reflections of the waves from the piece of equipment under test.

While there has herein been described illustrative embodiments of the invention, other embodiments within the scope of the appended claims will be apparent to those skilled in the art from the disclosure hereof and the teachings herein. For example, it will be evident that the invention can be readily applied to wave guides of types having a different geometry from the rectangular form shown in Figs. 3 and 4. Likewise if desired the block 24 may be divided into a larger number of sections instead of two as shown and such division in some instances as in cylindrical guides is especially desirable.

What is claimed is:

1. A terminal device for a guided wave system comprising: a transmission line section including coaxially disposed inner and outer conductors; a plug closing one end of said outer conductor; means passing through said plug and engaging the adjacent end of said inner conductor, for supporting said end of said inner conductor in spaced relationship to said outer conductor; means, adjacent the other end of said outer conductor and engaging said inner conductor along the length thereof, for similarly supporting the other end of said inner conductor; and a laminarily-wrapped covering of a material which is highly absorbent of electromagnetic energy, about said inner conductor; said covering filling the space between said inner and outer conductors at the end adjacent said plug and tapering substantially linearly along said inner conductor toward the opposite end of said section.

2. A terminal device for a guided wave system comprising: a transmission line section including coaxially disposed inner and outer conductors; a plug closing one end of said outer conductor; means passing through said plug and engaging the adjacent end of said inner conductor, for supporting said end of said inner conductor in spaced relationship to said outer conductor; means, adjacent the other end of said outer conductor and engaging said inner conductor along the length thereof, for similarly supporting the other end of said inner conductor; and a covering, consisting of cloth impregnated with a material which is highly absorbent of electromagnetic energy, wrapped about said inner conductor; said covering filling the space between said inner and outer conductors at the end adjacent said plug and tapering substantially linearly along said inner conductor toward the opposite end of said section.

3. A terminal device for a guided wave system comprising: a transmission line section including coaxially disposed inner and outer conductors; a plug closing one end of said outer conductor; means passing through said plug and engaging the adjacent end of said inner conductor, for supporting said end of said inner conductor in spaced relationship to said outer conductor; means, adjacent the other end of said outer conductor and engaging said inner conductor along the length thereof, for similarly supporting the other end of said inner conductor; and a covering, consisting of cloth impregnated with a material, containing carbon black in a form which is highly absorbent of electromagnetic energy, wrapped

about said inner conductor; said covering filling the space between said inner and outer conductors at the end adjacent said plug and tapering substantially linearly along said inner conductor toward the opposite end of said section.
